UNITED STATES PATENT OFFICE.

ROSARIO M. CANTILLO, OF NORRISTOWN, PENNSYLVANIA.

MAIL-BAG CATCHER AND DELIVERER.

No. 901,877.

Specification of Letters Patent.

Patented Oct. 20, 1908.

Application filed March 11, 1908. Serial No. 420,415.

To all whom it may concern:

Be it known that I, ROSARIO M. CANTILLO, a subject of Italy, who on February 24, 1908, at Norristown, Pennsylvania, filed his declaration to become a citizen of the United States of America, residing at Norristown, in the county of Montgomery and State of Pennsylvania, have invented new and useful Improvements in Mail-Bag Catchers and Deliverers, of which the following is a specification.

This invention relates to mail bag catchers and deliverers, and one of the principal objects of the same is to provide simple, reliable and efficient means for catching a suspended bag and carrying it into the door of a mail car and at the same time delivering a mail bag from the mail car to the post at the side of the track.

Still another object of the invention is to provide means for suspending the mail bags by means of cords or wires and to provide a series of fingers on the catcher and deliverer for releasing the cords which support the mail bags and transferring them.

These and other objects may be attained by means of the construction illustrated in the accompanying drawings, in which,

Figure 1 is a front elevation of a mail bag catcher and deliverer made in accordance with my invention. Fig. 2 is a plan view of the same. Fig. 3 is a side elevation of the mail bag catcher and deliverer in position to catch and deliver a mail bag. Fig. 4 is a detail plan view and partial section of the fork or fingers for engaging the suspending cord. Fig. 5 is a plan view of the upper end of the crane or stationary member of the device. Fig. 6 is a detail view of the trigger.

Referring to the drawings for a more specific description of my invention, the numeral 1 designates a mail car, and supported upon brackets 2 inside the car is a pair of arms 3, 4, said arms being pivoted upon a rod 5 which extends through said arms and through the brackets 2. The arm 3 is provided with a pair of fingers 6 which are spaced apart and provided with an intermediate slot. Pivoted to the plate 7 upon which the fingers 6 are formed is a disk 8 provided with a notch 9. When the disk 8 is turned in one direction the stop 9^a comes in contact with the projecting lip 9^b. Connected to the disk 8 is one end of a spring 10, the opposite end of which is connected to a staple 11 on the arm 3. A trigger 12 is con-

nected to a rod 13, and the outer end of the lever 12 engages a notch 14 in the disk 8. The rod 13 is provided with a spiral spring 15, and said rod is journaled in lugs 16 formed upon the arm 3. The trigger 12 is formed on an arm 17 provided with a rabbed end 18 which engages the similarly rabbed end of a bar 19 pivoted at 20 to a plate upon which the fork or fingers 21 are formed.

At the upper end of the rod 13 a disk 13^a is secured, said disk being provided with a notch 13^b. A spring stop or pawl 13^c is secured to the arm 3, the end of said stop bearing against the periphery of the disk 13^a and being adapted to spring into the notch 13^b when the rod 13 is turned in position to engage said parts. A knob 13^d on the spring stop 13^c serves as a finger hold to withdraw the spring from the notch.

The arm 4 at its outer end is provided with a series of fingers 22 spaced apart and provided with latches 23 pivoted at 24 and provided with a spring 25 to throw them outward to engage the next adjacent finger and prevent the suspending cord of the mail bag from removal therefrom. A rod 26 is journaled in the lugs 27 and provided with an encircling spring 28, one end of which is secured to the rod 26 and the opposite end to the lug 27, said rod 26 having an angular member 29 which holds the mail bag 30 against movement by the wind.

The crane or stationary member of the device comprises a post 31, to the upper end of which the arm 32 is pivoted upon a rod 33 journaled in brackets 34 on the post. The arm 32 is provided with converging braces 35, and on the end of the arm 32 are a series of fingers identical in structure with those shown in Fig. 4 of the drawing. A rod 36 is journaled in the braces 35 and is provided with a right-angular member 37 which is designed to hold the mail bag 38 against movement in the wind. A latch 39 on the arm 32 is adapted to engage a keeper 40 on the post 31 to hold the arm 32 against swinging upon its pivot 33.

Fingers 41 are spaced apart and adapted to support between them a ball 42 connected to a cord or wire 43 provided with a snap hook 44 engaging the mail bag 30. A similar ball 45 connected to a cord or wire 46 is provided with a snap hook 47 to engage the mail bag 38.

A cord 49 secured to an eye 49^a is led over

a pulley 50 and around a pulley 51, and secured to the end of the cord 49 is a weight 52.

The operation of my invention may be briefly described as follows: A mail bag 5 having been suspended by means of a cord and ball from between the fingers 6, and another mail bag having been suspended from between the fingers 41, the arms 29 and 37 10 are swung in position to prevent the wind from interfering with the operation of the device. As the mail car moves along in the direction indicated by the arrow in Fig. 2 the fingers 21 and 22 engage the cords 43 and 46 and withdraw the same from between the 15 fingers 6 and 41.

My invention is of comparatively simple construction, is strong, durable and efficient in use and can be readily installed.

Having thus described the invention, what 20 is claimed as new, is:—

1. A mail bag catcher comprising a pair of arms pivoted to the mail car, one of said

arms having a pair of fingers projecting therefrom and the other arm having a series of fingers comprising a catching fork, a post 25 provided with a crane having a series of fingers projecting therefrom, and an arm provided with a pair of fingers for supporting a mail bag by means of a cord and ball.

2. In a mail bag catcher, a pair of fingers, 30 a disk pivotally mounted between said fingers and provided with a notch, a spring connected to said disk, a trigger engaging a notch in said disk, and means whereby said trigger is actuated to release the disk, and a 35 mail bag suspended from a cord and connected to said disk.

In testimony whereof I affix my signature in presence of two witnesses.

ROSARIO M. CANTILLO
